United States Patent Office

Des. 225,142
Patented Nov. 21, 1972

225,142

CHAIR

Thomas Winrow, Naperville, Ill., assignor to Futorian Corporation, Amsterdam, N.Y.

Filed Dec. 3, 1970, Ser. No. 26,266

Term of patent 14 years

Int. Cl. D6—02

U.S. Cl. D6—31

The figure is a perspective view of a chair illustrating my new design.

The back of the chair is conventionally plain while the side not shown is substantially identical to the side shown.

I claim:

The ornamental design for a chair, substantially as shown and described.
